(57) **CLAIM**

The ornamental design for a paper towel dispenser, as shown and described.

DESCRIPTION

FIG. 1 is a top front perspective view of a paper towel dispenser, showing my new design;

FIG. 2 is a front elevation view thereof;

FIG. 3 is a rear elevation view thereof;

FIG. 4 is a right side elevation view, with the left side elevation view being a mirror image thereof;

FIG. 5 is a top plan view thereof;

FIG. 6 is a bottom plan view thereof; and,

FIG. 7 is an exploded perspective view thereof.

The broken line shown in FIG. 7 depicts the order of assembly and forms no part of the claimed design.

1 Claim, 4 Drawing Sheets(56)
